MEANS FOR EQUALIZING SHOCKS AT THE INJECTION OF FUEL INTO ENGINES
OPERATING ACCORDING TO THE SYSTEM SOLID INJECTION

Filed Nov. 21, 1924

UNITED STATES PATENT OFFICE.

AXEL UNO STURE DANIELSSON, OF STOCKHOLM, SWEDEN, ASSIGNOR TO AKTIE-BOLAGET ATLAS DIESEL, OF STOCKHOLM, SWEDEN, A CORPORATION OF SWEDEN.

MEANS FOR EQUALIZING SHOCKS AT THE INJECTION OF FUEL INTO ENGINES OPERATING ACCORDING TO THE SYSTEM SOLID INJECTION.

Application filed November 21, 1924, Serial No. 751,368, and in Sweden April 29, 1924.

At the injection of liquid fuel into the combustion chamber of engines by means of a force pump or the like ("solid injection") forcible shocks are effected in the conduit 5 extending from the ordinary overflow-valve controlled by a governor and adapted to return to the suction side of the pump the quantity of fuel superfluous for the driving of the engine at a certain load, said shocks 10 being due to the great pressure of the fuel and being able to untighten joint bolts and the like. Besides, the fuel owing to its great velocity often tears off pieces from joint packings, which pieces may accompany 15 the fuel and stick for instance in the suction valve of the pump and put the engine out of action. For the removing of the said shocks the engines, according to this invention, are provided with an air-receptacle 20 which communicates with the conduit for the superfluous fuel quantity and receives the said fuel and from which the fuel then returns, at reduced velocity, to the suction pipe of the pump or to the fuel receptacle.

25 In the accompanying drawing the top part of an internal combustion engine provided with a shock equilizing device is shown in vertical section.

30 In a head fixed in the top end of the working cylinder of the engine a cylinder 1 of a fuel pump is inserted, said cylinder 1 being in screw-threaded engagement with the head. The plunger 2 of the pump is actuated by the crank shaft of the engine. 3 is 35 the suction valve of the pump, permitting the fuel to pass sucked from a receptacle through a pipe 4. The fuel sucked into the pump is forced by the plunger 2 through a channel 5 to a valve for instance a needle valve leading to the working cylinder, which valve is opened by the fuel against the pressure of a spring and admits the fuel into the combustion-chamber of the engine and is shut, as soon as the pressure of the 40 fuel in the conduit 5 ceases. 6 is an overflow-valve, which communicates with the pump-cylinder through a channel 7. Between the valve 6 and a rod 10 slidable in a guide 8 and actuated by a spring 9, a spring 45 11 is located. A two-armed lever 13, which swings on an eccentric pin 12, extends with one arm under a flange on the rod 10 and, as the load of the engine varies, serves to raise the rod 10 at an earlier or later point of the

working stroke of the plunger 2, dependent 55 on the position of the eccentric pin 12, which is shifted by the governor of the engine by means of a motion transmitting device, not shown. Consequently, the surplus fuel not needed for the working stroke of 60 the engine is able to escape through the valve 6. Lever 13 is actuated for instance by a cam disc fixed on the crank shaft of the engine. As soon as the valve 6 has permitted the surplus fuel to escape and the 65 pressure in the channels and the pump cylinder is reduced at the return stroke of the plunger 2, the valve 6 is closed by the spring 11.

According to this invention the valve 6 at 70 its discharge side communicates with an air receptacle 14. In the form of execution shown as an example in the drawing the air receptacle is provided in the material of the cylinder head and a channel 15 provided in the said material extends from the valve to the air-receptacle. With the bore provided for the air-receptacle a hallow plug 16 is in screw-threaded engagement, between which and the wall of the bore there is a space 17, into which the channel 15 opens. From the lower part of the air-receptacle a pipe 18 extends to the suction pipe 4 of the pump.

Engines, arranged according to the system "solid injection" generally operate with 85 a very high pressure (300 to 400 atmospheres) on the injected fuel. The result is that the fuel passing through the overflow-valve 6 escapes at a very great velocity. The shocks in the conduits etc. and other inconveniences, hitherto caused by the fuel rushing forth, are removed by the air-receptacle, owing to the fact that the fuel enters the same compressing the air contained 90 in the receptacle and for that reason escapes 95 at a considerably reduced speed through the pipe 18 to the fuel-receptacle or the suction pipe 4. In the form of execution of the air-receptacle shown in the drawing the space 100 17 between the plug 16 and the inner side of the bore is filled with fuel. Fuel ascends to a certain level in the plug 16, in the top part of which the air-cushion is provided. As, owing to this arrangement, the fuel 105 passing from the valve 6 through the channel 15 strikes exclusively fuel in the air-receptacle and by the plug is prevented from spouting into the air, the generating of bub-

bles is entirely excluded. Air, contained in the entering fuel, collects in the top part of the space 17 and is permitted to escape through an outlet provided at 19 and controlled by a screw.

The air-receptacle may, evidently, be located at any other suitable place and its construction may differ from that illustrated in the drawing.

10 I claim:

1. In a feeding device for liquid fuel for internal combustion engines, the combination with a pump and an overflow valve, a branch conduit connecting said overflow valve with the suction side of said pump, and a chamber in said branch conduit, said chamber being adapted to provide an air cushion to equalize the flow of fuel during the injection operation.
- 15 2. In a feeding device for liquid fuel for internal combustion engines, the combination with a pump and an overflow valve, a branch conduit connecting said overflow

valve with the suction side of said pump, a chamber in said branch conduit, and a second chamber communicating with said first mentioned chamber through a liquid seal. 25

3. In a feeding device for liquid fuel for internal combustion engines, the combination with a pump and an overflow valve, a 30 chamber, a branch conduit connecting the suction side of said pump with the bottom of said chamber, a hollow plug adapted to be inserted in the top of said chamber, said plug being provided with a reduced portion 35 at its lower end to provide an annular space between the plug and the wall of said chamber, said lower end being spaced from the bottom of said chamber, and a second conduit providing communication between said 40 overflow valve and said chamber at a point in the chamber above the lower end of said plug.

In testimony whereof, I have hereunto signed my name.

AXEL UNO STURE DANIELSSON.
